UNITED STATES PATENT OFFICE.

OLIVER C. MOORE, OF CLEVELAND, OHIO.

EXPANSION-PISTON LAPING-IN TOOL.

Application filed January 15, 1921. Serial No. 437,576.

To all whom it may concern:

Be it known that I, OLIVER C. MOORE, a citizen of the United States, and a resident of Cleveland, county of Cuyahoga, and State of Ohio, have invented a new and useful Improvement in Expansion-Piston Lapping-In Tools, of which the following is a specification, the principle of the invention being herein explained, and the best mode in 10 which I have contemplated applying that principle, so as to distinguish it from other inventions.

This invention relates to a lapping-in tool in the form of an expansion piston. More 15 particularly, it comprises, in one of the forms of its construction, four quarter sections, which sections are held in spaced relation to one another, forming a cylindrical member, upon a tapered central member by 20 means of a series of inwardly extending flanges bearing upon the surface of such tapered central member and adjustable relatively thereto.

Heretofore, in lapping-in engine cylinders, it has been customary to use pistons having cracked lower portions or discarded pistons of smaller size, provided with slots cut into their lower edges and wedged to the size desired. Such makeshift implements 30 give much trouble in attempting to produce satisfactory work, inasmuch as they are frequently out of round and are subject to breakage and uneven wear. Likewise, the proper distribution of the abrasive substance 35 is in no way provided for and accurate work is impossible with such appliances.

The principal object of my invention is to avoid the disadvantages noted, by supplying a lapping-in tool of such character that 40 it may be accurately fitted in circumferential adjustment to the work in hand and may, if desired, be readjusted during the progress of the work.

Further objects of my invention will appear in the course of the following description, among them being the provision of 45 grooves for the proper distribution of the abrasive substance used, as well as a reservoir to hold the abrasive substance for distribution to such grooves. To the accomplishment of the foregoing and related ends, said invention, then, consists of the means hereinafter fully described and particularly pointed out in the claims.

The annexed drawing and the following 55 description set forth in detail certain mecha-

nism embodying the invention, such disclosed means constituting, however, but one of various mechanical forms in which the principle of the invention may be used.

60

In said annexed drawing:

Fig. 1 is a transverse vertical sectional view showing my complete apparatus in assembled relation; Fig. 2 is a transverse horizontal section taken along the line 2—2 65 shown in Fig. 1 looking in the direction of the arrows; Fig. 3 is a plan view partially in section taken along the line 3—3 in Fig. 1 looking in the direction of the arrows; Fig. 4 is a side elevation of the outer face of one 70 of the sections showing the spring grooves, abrasive supply duct, and connecting channelways; Fig. 5 is a perspective view of one of the piston sections showing its interior construction and the manner of fitting the 75 abrasive supply elements thereto; and Fig. 6 is a transverse horizontal sectional view showing a modified form of my apparatus whereon an inner tapered element of rec- 80 tangular cross-section is used.

As illustrated in the drawing, a tubular member or stem 1 has mounted on its upper end a handle 2 and upon its lower end a circular plate 3. Within said tubular member is positioned a rod 4, the lower end of 85 which carries a screw-threaded portion 5 upon which is engaged an internally threaded conical member 6, which may be of any desired cross-section, depending upon the particular use to which the tool is to be 90 put and the number of lapping-in sections employed, such form being circular as shown in Figs. 1, 2 and 3, and rectangular as shown in Fig. 6. The upper end of said rod is of smaller diameter than its main section 95 and it terminates in a portion 7 of squared or other suitable cross-section to permit the engagement therewith of a wrench or other operating member. Inwardly of said squared portion the rod is screw threaded for a 100 short distance to provide for the engagement of a locking nut 8 which positions an apertured plate 9 against the shoulder 11 provided by the enlarged section of the rod. The plate 9 is secured to the handle and 105 stem by any suitable means. As shown in Fig. 1 the plate is provided with screw-threads 12 about its outer periphery and is seated within a recess 13 provided in the upper face of the handle.

The lapping-in portion of the tool consists of a plurality of sections 15 of a hollow

110

2
cylindrical member, which are provided upon their inner sides with inwardly extending lugs 16, 17, of a shape suitable to ride against the surface of the conical or tapered member 6 upon the rod, heretofore referred to, and are of such graduated length as to maintain the outer sides of said cylindrical sections in vertical position, whatever position longitudinally they occupy with respect to such tapered member.

10 To maintain the cylindrical sections in proper spaced relation about the tapered support, I preferably provide a series of ribs or projections 21 and cooperating grooves or notches 22 centrally of the bearing surfaces of said lugs and upon the adjacent surface of the supporting member, respectively. In the modified form shown in Fig. 6 the flat faces 23 of the tapered member of rectangular cross-section 24, of themselves serve to position the cylindrical sections. Co-acting ribs and grooves may be employed however to key the parts into position as in the other construction described, but, as shown in Fig. 25 6, the ribs 25 are provided on the tapered member and the grooves 26 upon the flat faces 27 of the lugs 28. Obviously the position of these parts may be reversed as desired, in view of considerations of ease of manufacture and assembling.

30 The upper edges of each of these cylinder sections are provided with inwardly extending flanges designed to rest upon the circular plate 3 upon the end of the tubular stem heretofore referred to. They are held in clamped relation to this plate by means of a clamping disk 29, suitably notched to allow free radial movement for the tubular abrasive supply ducts, and held in position by a locking member 30 threadedly engaged upon the stem 1 and adjustable thereon by means of a hand-wheel 34.

35 Each of the cylinder sections is provided with a plurality of transverse grooves 31, 32 about its circumference within which are placed coil spring bands 33 which serve to maintain said cylinder sections in close engagement with the tapered central member. The grooves are made deeper than necessary to accommodate the springs in order to provide a small amount of space at the outer side thereof for the reception and distribution of the abrasive mixture used. This abrasive mixture, consisting ordinarily of 40 carborundum and oil, is preferably supplied to the grooves by wiping the same therein prior to the insertion of the tool in the cylinder, but the supply is maintained through a tubular passageway or duct 35 communicating with a reservoir in the form of an oil cup 36 held vertically above the flange at the upper edge of each of the cylinder sections and passing through the side wall of said section at a central point thereof midway of the two spring grooves heretofore

described. Diagonal channel-ways 37 cut into the outer surface of each of the cylinder sections afford a means of communication from the oil duct aperture to adjacent parts of the respective spring grooves.

70 From the construction above described, it will be noted that means for adjusting the diameter of the sectional cylinder has been disclosed, as well as means for locking the same into any predetermined adjusted position. When it is desired to make a new adjustment, the hand-wheel 34 upon the clamping member 30 is rotated to unlocking position and the squared end 7 of the rod 4 within the tubular handle portion 1 is then rotated until the desired diameter of the sectional cylinder is obtained. The clamping wheel is then turned to locking position.

75 The manner in which my tool is used after being thus adjusted, in a measure, is similar to that employed with the make-shift tools heretofore described. Thus, abrasive compound may be supplied to the surface of the lapping-in tool by turning down the plungers on the cup reservoirs and the tool is then 80 manually shifted up and down in the interior of the cylinder to be ground to proper size, and during the course of such reciprocation, is oscillated back and forth so as to 85 present a new surface of the tool to the part 90 worked upon, at periodic intervals. With the use of the ordinary tool, it is necessary, after a certain amount of work has been accomplished, to withdraw the tool and manually renew the supply of abrasive mixture, 95 but with the tool I have provided, the abrasive mixture originally supplied within the 100 spring groove 5 is continuously added to from the reservoirs I have provided on each 105 of the cylinder sections and the implement is thus suitable for continuous operation. The abrasive mixture used is maintained of 110 uniform character through the use of my apparatus and a great saving in the amount used will also result. Thus the work of lapping-in engine cylinders may be most accurately and economically accomplished.

115 Other modes of applying the principle of my invention may be employed instead of the one explained, change being made as regards the mechanism herein disclosed, provided the means stated by any of the following claims or the equivalent of such stated means be employed.

I, therefore, particularly point out and 120 distinctly claim as my invention:—

1. A lapping-in tool, comprising a pair of 125 relatively movable supporting members, a sectional cylinder supported upon one of said supporting members, coacting means supported upon the other of said supporting members for enlarging the effective diameter of said cylinder, and resilient means for holding said cylinder sections together.

2. A lapping-in tool, comprising a pair of relatively movable supporting members, a sectional cylinder supported upon one of said supporting members, a reservoir for abrasive mixture associated with said cylinder sections, channel-ways upon the surface of said cylinder sections for distributing said mixture, tubular means connecting said reservoirs and said channel-ways, and coacting means supported upon the other of said supporting members for enlarging the effective diameter of said cylinder.
3. In a tool for the purpose set forth, in combination, a longitudinally split sectional shell, resilient means for retaining said shell sections together, said sections provided with horizontal partitions, a central conical spreader passing through openings in said partitions, a screw rod for adjusting the said spreader, a sleeve in which said rod is rotatable, and securing means for rod, and means for detachably clamping said sleeve to said sectional grinding shell, said cylindrical shell provided with peripheral recesses adapted to retain abrasive material.
4. In a tool for the purpose set forth, in combination, a sectional grinding shell, provided with spaced conical central openings, a conical spreader therein, an adjusting screw therefor, means for supporting said screw, and means for detachably securing said supporting means to said sections.
5. In a tool for the purpose set forth, in combination, a longitudinally split sectional shell, resilient means for retaining said shell sections together, said sections provided with horizontal partitions, a central conical spreader passing through openings in said sections, channel-ways upon the surface of said cylinder sections for distributing said mixture, tubular means connecting said reservoirs and said channel-ways, and coacting means supported upon the other of said supporting members for enlarging the effective diameter of said cylinder.
10. In a tool for the purpose set forth, in combination, a longitudinally split sectional shell, resilient means for retaining said shell sections together, said sections provided with horizontal partitions, a central conical spreader passing through openings in said sections, channel-ways upon the surface of said cylinder sections for distributing said mixture, tubular means connecting said reservoirs and said channel-ways, and coacting means supported upon the other of said supporting members for enlarging the effective diameter of said cylinder.
15. In a tool for the purpose set forth, in combination, a longitudinally split sectional shell, resilient means for retaining said shell sections together, said sections provided with horizontal partitions, a central conical spreader passing through openings in said sections, channel-ways upon the surface of said cylinder sections for distributing said mixture, tubular means connecting said reservoirs and said channel-ways, and coacting means supported upon the other of said supporting members for enlarging the effective diameter of said cylinder.

Signed by me this 8th day of January, 1921.

OLIVER C. MOORE.
